TENNIS RACQUET HOLDER AND SHELF

Donald C. Trieschmann, 615 Cherry St.,
Winnetka, Ill. 60093

Filed Nov. 21, 1973, Ser. No. 417,878

Term of patent 7 years

Int. Cl. D6—06

U.S. Cl. D6—114

FIG. 1 is a perspective view of a tennis racquet holder and shelf embodying my new design;

FIG. 2 is a front elevational view thereof;

FIG. 3 is a rear elevational view thereof;

FIG. 4 is a side elevational view thereof;

FIG. 5 is a top plan view thereof; and

FIG. 6 is a bottom plan view thereof.

I claim:

The ornamental design for a tennis racquet holder and shelf, substantially as shown.
